UNITED STATES PATENT OFFICE.

WILLIAM PRESTON PHENIX, OF LUBBOCK, TEXAS.

VICE.

SPECIFICATION forming part of Letters Patent No. 693,149, dated February 11, 1902.

Application filed June 5, 1901. Serial No. 63,246. (No model.)

To all whom it may concern:

Be it known that I, WILLIAM PRESTON PHENIX, a citizen of the United States, residing at Lubbock, in the county of Lubbock and State of Texas, have invented certain new and useful Improvements in Vises; and I do hereby declare the following to be a full, clear, and exact description of the invention, such as will enable others skilled in the art to which it appertains to make and use the same.

My invention relates to certain new and useful improvements in vises, the preferred materialization whereof will be fully set forth in the following specification and illustrated in the accompanying drawings, made a part of this application.

The object of my invention is to provide certain accessories designed to coöperate with the jaws of the vise in such a manner that the jaws will be very quickly and tightly brought together into direct engagement or into engagement with any object interposed between them.

A further object of my invention is to provide an attachment for an old worn-out vise which will restore the jaws thereof to usefulness.

Other objects and advantages will be made fully apparent from the following specification considered in connection with the accompanying drawings, in which—

Figure 1 is a central vertical section of my improved vise complete ready for use. Fig. 2 is a side elevation of my improved vise, showing a slightly-modified construction. Fig. 3 is a perspective detail view of the wrench portion of the controlling mechanism. Fig. 4 is a central longitudinal section of Fig. 3 on a slightly-reduced scale. Fig. 5 is a side view of my improved controlling-bar removed from the other coöperating parts of my vise, showing a modification. Fig. 6 is a perspective detail view of one end of the controlling rack-bar. Fig. 7 is a top plan view of my vise complete. Figs. 8 and 9 show how my invention may be readily attached to the jaws of an old vise.

In order to conveniently designate the several parts of my invention and the elements designed to coöperate therewith, numerals will be employed, of which—

1 indicates the work-bench or other support

upon which the body portion 2 of my device is operatively mounted, as by means of the locking-bolts 3, extending through suitable ears 4, integrally formed upon said body portion. The body portion may be additionally secured by means of the downwardly-extending bracket 5, also preferably formed integral with the body portion and having a suitable aperture through which the locking-bolt may extend into engagement with a contiguous part of the table.

The body portion 2 is integrally formed with the stationary or fixed jaw 7, designed to coöperate with the movable jaw 8, both of which are constructed substantially in the usual or any preferred manner. The body portion 2 is provided with the extension 9, upon which the movable jaw 8 is adapted to move when moved into its operative position. Both the jaws are provided with a centrally-disposed bore adapted to receive the clamping rack-bar 10, which is provided upon its upper surface with the oppositely-disposed series of racks or teeth 11 and 12 for a purpose hereinafter clearly set forth. In the form of rack-bar illustrated in Fig. 1 I have shown one end as having the transversely-disposed aperture 13, while the opposite end 14 is threaded, the latter being adapted to receive a threaded bore provided in the controlling-thimble 15, which latter has upon its outer end a suitable aperture designed to receive the controlling handle or lever 16, whereby the said rack-bar may be so acted upon by said thimble that the movable jaw will be forced toward or away from the stationary jaw, as may be desired. The movable jaw is also preferably provided with the extension 17, the outer end of which is adapted to afford a seat against which the inner end of the thimble 15 may be brought to bear. Designed to coöperate with the teeth on the inner end of the rack-bar is the pivoted pawl or detent 18, having the axis or rivet 19, which latter is passed through contiguous ears or portions of the fixed jaw, as will be clearly seen by reference to Fig. 1. The detent 18 is held normally downward by means of the controlling-spring 20, which latter is anchored at a convenient point on the fixed jaw, as indicated by the numeral 21, the free end of the spring being thus left to bear upon the outer end of

said detent. In order that said detent may be placed fully under the control of the operator, I provide in its outer end the slotted guideway 22, designed to afford means for connecting the detent to the upper end 23 of the pivoted lever 24, said lever being secured to the fixed jaw by means of the rivet or bolt 25. The pivoted lever 24 is operatively connected to the treadle 26 by means of the rod 27, and it is obvious that a downward pressure upon said treadle will cause the elevation of the detent, so that the teeth upon the lower edge thereof will be lifted out of engagement with the contiguous teeth upon the rack-bar 10, and thus permit said bar to move longitudinally.

The rack-bar 10 is held normally inward by means of the spring 28, which is mounted in a suitable bore 29 in a contiguous part of the body portion 2, a slotted guideway 30 being formed in said body portion, so that the stem 31, connected to the under side of the rack-bar, may be engaged by the outer end of said spring, as more clearly shown in Fig. 1.

The movable jaw 8 is held normally away from the fixed jaw by means of the spring 32, which latter is secured, preferably, to the downwardly-extending bracket 5 by means of the bolt 6. The spring 32 may be bifurcated upon its free end, so that a branch thereof may be brought to bear upon an extension formed upon the movable jaw, the branches being disposed upon either side of the extension 9, formed upon the body 2.

If desired, the thimble 15 may be dispensed with and that form of thimble illustrated in Fig. 3 substituted therefor, wherein it will be observed that the body portion 33 is provided at its inner end with a square, octagonal, or other form of opening, as designated by the numeral 34, which opening is designed to receive a correspondingly-shaped nut 35, secured on the threaded end of the rack 10, as shown in Fig. 5, the outer end of the thimble being provided with an aperture 36, adapted to receive the handle 16, whereby the thimble may be freely rotated in either direction.

In Fig. 5 I have also illustrated how the rack-bar 10 may be very quickly moved, so as to close the jaws, inasmuch as I employ the controlling-head 37, which is provided with a suitable opening 38, adapted to receive the contiguous end of the rack-bar, to which it is eccentrically pivoted by means of the bolt 38^x, extending through the aperture 18, and since the peripheral face of said controlling-head may be brought to bear firmly against the end of the jaw represented by dotted lines in Fig. 5, which in this instance is the movable jaw, it is obvious that said jaw may be instantly forced toward the stationary jaw, and thereby insure that any interposed object will be firmly grasped and held until released by an opposite movement of the controlling-lever 39. The controlling-head 37 may be used independently of or in coöperation with the controlling-lever 16 and accompanying thimble, as may be desired,

though it is thought that but one of said controlling devices will be found amply sufficient to meet all requirements. If both of said devices are employed, a suitable extension formed upon the stationary jaw should be provided, against which the peripheral face of the controlling-head 37 may be brought to bear by a movement of the lever 39.

In Figs. 8 and 9 I have illustrated how my invention may be readily and efficiently applied to use upon the jaws of an old vise, the coöperating threaded shaft or screw whereof has become useless from wear. The threaded bar 10 is used upon the old jaws substantially as shown in Fig. 1, except that the thimbles 40 and 41 are provided, each of which is to be properly seated in the threaded hole occupied by the screw of the vise, said thimbles being secured therein in any preferred way, as by threading the thimbles and screwing them home or otherwise. The detent 18 is pivotally secured in a suitable recess provided in the flange of the thimble at a convenient point where it will readily engage the teeth 12 upon the rack-bar 10, whereby the said rack-bar may be readily placed under the control of the operator, as hereinbefore specified. In Fig. 8 the jaws of an old vise are indicated by the numerals 42 and 43, which are of the usual or any preferred construction, and it is obvious that by mounting the rack-bar and its coöperating parts in position by means of said thimbles 40 and 41, or the equivalent thereof, I am able to render the jaws of an old vise very useful and efficient even after the threaded screw coöperating therewith has been destroyed by use.

The various parts of my improved vise may be very cheaply and expeditiously manufactured and readily assembled in their operative positions, and while I have described the preferred construction which may be adapted in materializing my invention I desire to comprehend in this application all substantial equivalents and substitutes that may be considered to fall fairly within the scope of my invention.

Having thus fully described the construction of my improved vise and coöperating accessories, the manner of using the same may be stated to be as follows: The fixed and movable jaws are properly assembled and the controlling-bar 10 extended through the opening provided in said jaws, so that the teeth 12 will be disposed under the detent 18 and in engagement therewith, it being seen that said bar may be readily pushed under said detent, inasmuch as the inclination of the teeth upon said parts will permit the inward movement of the bar, but check its outward movement until the detent is raised. When the parts are thus assembled, the object upon which it is desired to bring the jaws to bear is interposed between them and the movable jaw pushed into close engagement by the hand of the operator, which will cause the bar 10 to move inward, such inward movement being

secured by the detent 18. When the jaws have been brought into engagement with the object interposed between them, the lever 16 may be grasped, and the thimble 15 or 33, as 5 the case may be, turned sufficiently to finish the clamping process and insure that the interposed object will be very firmly secured until a reverse rotation of said thimble will release it. In case the lever 16 and accompanying thimble is dispensed with and reliance placed upon the controlling-head 37 then and in that event the bar 10 may be reversed and the threaded end thereof entered first, so 10 that the teeth 11 will be engaged by the detent 18, it being understood that the post 31 is withdrawn from its aperture and entered into an aperture in the opposite end of the bar. The jaws may then be manually brought together, so as to bear upon the interposed 15 object, when a downward movement upon the lever 39 will bring the peripheral face of the head 37 into engagement with the extension 17, and thus finish the locking process of the jaws.

25 The description above set forth comprehends the interchangeability of the controlling coöperating elements for the bar 10, it being understood, however, that full reliance may be placed upon the controlling-head 37 or 30 the thimbles 15 or 16 without the necessity of adapting the bar 10 for both of said devices.

The thimble 15, it will be observed, is provided with a threaded bore adapted to directly act upon the threaded end of the bar 35 10, while the thimble 33 is formed with a suitable opening adapted to indirectly act upon said bar through the mediation of the nut 35, the thimble in this instance forming the office of an ordinary wrench, which latter may be 40 used as a substitute, if desired.

My improved vise will be found very desirable and efficient for all of the purposes for which such an instrument is useful, inasmuch as it may be very quickly mounted in 45 its operative position upon any suitable form of supporting-base. The parts being of simple character and construction may be formed in quantities, and thus rendered interchangeable, so that when one part becomes impaired 50 or destroyed by use it may be quickly replaced and the vise substantially restored to its original condition without the necessity or expense of renewing all of the parts.

Having thus fully described my improved 55 vise, what I claim as new, and desire to secure by Letters Patent, is—

1. The herein-described vise having a stationary and movable jaw, the former being provided with an extension for supporting the 60 movable jaw; a rack-bar having oppositely-disposed teeth upon opposite sides of its transverse center; a detent carried by one of said jaws; means to hold said jaws normally open and additional means substantially as described for forcing said jaws tightly in en-

gagement with each other or in engagement with any interposed object, all combined substantially as specified and for the purpose set forth.

2. The combination with a stationary jaw 70 and a movable jaw having portions slidable one over the other, of a rack-bar having oppositely-disposed teeth upon opposite sides of its transverse center, a controlling device engaging a threaded end of the rack-bar, a pivoted toothed detent carried by the stationary jaw to engage the teeth of the rack-bar, means for holding said detent in operative position and means engaging the detent for limiting its movement substantially as described. 80

3. The combination with a stationary jaw and a movable jaw having portions slidable one over the other, of a rack-bar having oppositely-disposed teeth upon opposite sides of its transverse center, a controlling device 85 engaging a threaded end of the rack-bar, a pivoted toothed detent carried by the stationary jaw to engage the teeth of the rack-bar, means for holding said detent in operative position and means engaging the detent for limiting 90 its movement, the stationary jaw having its body portion formed with a slotted guideway and a downwardly-dependant stem carried by the rack-bar movable in said guideway, substantially as described. 95

4. The combination with a stationary jaw and a movable jaw having portions slidable one over the other, of a rack-bar having oppositely-disposed teeth upon opposite sides of its transverse center, a controlling device 100 engaging a threaded end of the rack-bar, a pivoted toothed detent carried by the stationary jaw to engage the teeth of the rack-bar, means for holding said detent in operative position and means engaging the detent for limiting 105 its movement, the stationary jaw having its body portion formed with a slotted guideway and a downwardly-dependant stem carried by the rack-bar movable in said guideway, and a spring acting upon said stem to normally 110 hold the rack-bar inward, substantially as described.

5. The combination with the stationary jaw having a horizontal body portion with longitudinal bore and longitudinally-disposed slotted guideway, of a movable jaw, a rack-bar passed through both of said jaws, means for operating the rack-bar, and a stem depending from the rack-bar and movable through said slotted guideway and a spring within said 115 bore and acting upon the lower end of said stem which projects into said bore through the guideway all substantially as shown and described.

In testimony whereof I affix my signature 125 in presence of two witnesses.

WILLIAM PRESTON PHENIX.
